GRINDING MACHINE

Application filed June 4, 1927. Serial No. 196,579.

This invention relates to a grinding machine and more particularly to a machine which will serve to grind a multiplicity of duplicate work pieces simultaneously, it being understood that the various operations known as lapping, polishing, honing, abrading and grinding are all grinding operations, in the broader meaning of the expression.

Various types of machines, known as 10 grinding or lapping machines, have been proposed for grinding a plurality of work pieces in which the work pieces have been mounted in a cage between two opposed elements provided with plane annular abrading faces and 15 either one or both of the annular elements or the work cage has been rotated to produce a relative movement between the work and the elements. In such machines, the two annular elements have been made of various materials depending upon the type of grinding 20 operation desired. They are ordinarily made of abrasive materials, such as that of an ordinary grinding wheel, or of metal, such as iron, which is used with loose abrasive 25 grain and oil, or which is charged with abrasive grains. In a machine of this type, the abrading action is caused by a sliding motion of the work relative to the annular abrading elements, if the work is flat surfaced, or by a 30 combined rolling and sliding motion, if it is round.

This operation as heretofore practiced is intermittent and non-automatic since the work pieces are manually loaded into the cage and subsequently removed and inspected by the operator before the machine is re-loaded with a new supply of work pieces and the lapping operation repeated. Such a machine is necessarily expensive to operate on 35 a production basis owing to the loss of time involved and to the slowness of the lapping operation. There is a need for an automatic machine in which the work pieces will be fed automatically into the grinding zone, then ground to the desired size and automatically discharged therefrom, so that the operating cycle will be a continuous one.

It is accordingly one object of my invention to overcome such disadvantages and to provide an automatic machine which will serve

to grind a large number of round work pieces simultaneously and in which the pieces are fed successively into the grinding zone without stopping the grinding operation.

It is a further object of my invention to 55 provide a machine which will operate automatically to grind a large number of pieces of work simultaneously and to reduce them successively to a predetermined size.

It is another object of my invention to provide a machine in which the work may be fed automatically to the grinding element, 60 sized in a single pass through the machine and then automatically discharged.

A still further object is to eliminate or 65 minimize the non-productive period of a grinding operation and particularly to provide a fully automatic grinding machine which may be used for finely or roughly sizing a large number of work pieces and giving 70 them a desired finish without requiring skillful attention on the part of the machine operator.

With these and other objects in view as will be apparent to one skilled in the art, my invention resides in the combination of parts set forth in the specification and covered by the claims appended hereto.

In accordance with my invention, I provide a grinding machine having a cage for 80 holding a multiplicity of work pieces in operative relation to two opposed annular elements arranged to grind the work, and which is so constructed and arranged that the work pieces may be fed to and removed from the 85 machine automatically so that the machine may operate continuously for grinding a succession of pieces.

My invention further contemplates the provision of a grinding machine which causes 90 a multiplicity of work pieces to be ground simultaneously and reduced successively to a predetermined size before they are discharged from the machine, and this is preferably accomplished by means of a construction in which the work makes a single pass through the grinding zone.

In the specific embodiment of the invention illustrated in the drawings, I have there shown a machine having an upper rotatable 100

member and a lower stationary member, each of which is provided with an annular face adapted to cooperate with a rotatable work cage located therebetween to grind a plurality of work pieces simultaneously. The annular elements may each be made as desired, either of abrasive material or of non-abrasive material and they may be so mounted and arranged that the space therebetween 10 may be adjusted to accommodate various sizes of work pieces. In order that the work may be transported automatically and successively through the grinding zone, it is preferable that the lower or stationary annular element 15 be so shaped and arranged that as a piece of work travels along its surface, the center of the work may gradually approach the other element. In other words, this stationary element may be shaped to provide an inclined surface between two points so that as the work travels from the lower to the higher point, it will be reduced in size.

In order to introduce the work automatically into the grinding zone a feeding device 25 is arranged to present the work pieces successively to the cage. One mechanism suitable for this purpose, as illustrated in the drawings, comprises an oscillating arm arranged to receive the work pieces from a chute and present them successively to the revolving cage. The work similarly may be removed from the grinding zone by a suitable discharge device. This may comprise an opening in the stationary annular grinding 35 element which is so arranged that the work pieces may travel substantially through one revolution through the grinding zone while remaining in the work cage.

The work is preferably given a path which 40 is eccentric relative to one of the abrading members, and preferably the rotatable member, so as to cause it to contact with the entire operative face and cause even wear thereof. In carrying out a lapping operation it is 45 preferable that both the cage and the upper rotatable abrading element be rotated slowly and that the work slide relative to both of the annular elements and not merely roll thereon. It will also be observed that the 50 work is arranged in a substantially radial position in the cage and this further causes a sliding motion of the work relative to the annular elements as it traverses through the grinding zone. The rates of motion of the 55 two elements may be varied as desired by the operator, in accordance with the nature of the work and the type of grinding operation desired.

Referring to the drawings which illustrate 60 a simple form of one embodiment of my invention and in which like reference numerals indicate like parts:

Figure 1 is a side elevation of the machine having parts broken away to more clearly 65 show the construction;

Fig. 2 is a front elevation, parts of the base being broken away to show the work feeding mechanism;

Fig. 3 is a fragmentary elevation showing somewhat diagrammatically the relation of 70 the grinding wheel, the work carrying cage and the work supporting member;

Fig. 4 is a plan view similarly showing the relations of the main parts;

Fig. 5 is an enlarged fragmentary view of 75 a portion of the work driving cage and the work feeding mechanism;

Fig. 6 is a development of the operative portion of the track and the wheel showing 80 the relation therebetween and illustrating the reduction in size of work as it revolves;

Fig. 7 is an enlarged fragmentary view of 85 a portion of the cage showing the adjustable thrust screws for positioning the work;

Fig. 8 is an end elevation of the work supporting member removed from the machine, but with the curve of the track exaggerated;

Fig. 9 is a detail of a modification of the track;

Fig. 10 is a detail showing the work feeding mechanism;

Fig. 11 is a detail partly in elevation and 95 partly broken away of a modified form of track and devices for adjusting the same;

Fig. 12 is a top plan view of the track and adjusting arms removed from the support.

As shown in the drawings, I have illustrated a grinding machine having a base 10 carrying an annular abrasive element 11 mounted on a rotatable spindle 12. The upper end of the spindle 12 is provided with a pulley 13 arranged to be rotated by a belt 14 passing over the idler pulley 15 from any suitable source of power. Opposed to the plane of 100 the operative surface of the rotatable element is a stationary annular member 17 mounted upon a portion of the base of the machine. A work cage 18 is mounted for rotation between the operative surfaces of 110 both annular elements and it is so constructed and arranged that, as it rotates, it causes the work pieces 19 to revolve about the cage center while it imparts a sliding movement to them relative to both annular members. The 115 grinding elements may be made of metal and used with an abrading compound or they may be made of other suitable material, such as an abrasive body similar to the grinding wheel, the grain and grade and other 120 characteristics of the body depending upon the nature of the work and the operation to be performed.

In the preferred construction, the annular elements are mounted with their axes in a 125 vertical plane, with the rotatable member above, and in order that proper adjustments may be made between the rotatable member and the stationary member, I preferably mount the rotatable member in a housing 20 130

carried on an arm 21 projecting from the upright 22 of the base 10. The spindle 12 is rotatably mounted in a hollow sleeve 26, which is slidably mounted within the housing 20 but is held against rotation therein by a key 27 adapted to slide in a keyway 28 in the housing. The upper end of the sleeve 26 is provided with a threaded portion 29 surrounded by a hand wheel 30 having a correspondingly threaded aperture. The lower face of the hand wheel bears against the upper face of the housing 20. In the simplified construction illustrated the weight of the upper rotatable member and sleeve construction 15 is considered sufficient to hold the rotatable member down under the thrusts of grinding. It will be readily seen that by turning the hand wheel 30 the rotatable member may be raised or lowered relative to the stationary member to permit adjustment of the upper member for different sizes of work or to compensate for wear of the operative surface of the wheel.

The stationary annular member may be mounted directly upon the base of the machine if desired, but in my preferred construction, it is carried on a slide 35 adapted to be adjusted transversely on the dovetailed slideway 36 on the base of the machine. To 25 provide for such adjustment of the slide, I may utilize any suitable mechanism such as a nut and screw. This construction comprises a nut 37 mounted on the under surface of the slide 35 and a screw 38 mounted for rotation 30 but held against endwise movement in a portion of the base, which is arranged to engage the threaded portion of the nut 37. A hand wheel 39 is mounted on the outer end of the screw 38 to permit the slide to be adjusted 35 transversely of the machine. By turning the screw 38, the stationary member 17 may be adjusted to vary the eccentricity of the upper and lower elements, so that as the work enters the machine, the outer ends of the 40 45 rolls to be ground may contact with the rotatable member at a point adjacent its outer periphery and at a position diametrically opposite, as viewed in Fig. 3, the inner end of the work may be adjacent to the inner periphery of the rotatable member.

The work carrying cage 18 is mounted on the upper end of a vertical shaft 40 supported in suitable bearings 41 in the slide 35. The lower end of the shaft 40 is provided 50 with a gear 42, meshing with a smaller gear 43 which is mounted on a shaft 44 supported in bearings in the slide 35. The shaft 44 may be rotated from any suitable source of power (not shown) such as a motor in the base or 55 the like.

One suitable feeding mechanism for introducing the work involves means to present the pieces one by one to work receiving portions of the cage. As shown in Figs. 65 1, 5 and 10, the work slides down the chute

45, the lower end of which is mounted on the slide 35, and onto the work supporting carrier plate 46 of the work feeding member 47. The member 47 is a lever pivotally mounted on a stud 48 which is supported on the slide 70 35 and it is normally held with the carrier plate 46 in an upper position by means of a spring 50, one end of which is attached to the slide and the other end to the outer end of the lever 47. The upward movement of the 75 surface 46 is limited by a stop 51 projecting from the under side of the lever 47 to engage the top of the slide. The lever 47 is provided with an upwardly projecting arm 55 adapted to contact with the blocks 56 on the 80 outer periphery of the work cage 18.

As the cage rotates in the direction of the arrow, as shown in Figs. 2 and 5, the block 56 contacts with the projection 55 and swings the lever 47 so that carrier 46 is moved downwardly into alignment with the lower surface of the chute 45. This permits a piece of work to slide downwardly under the influence of gravity onto the carrier 46. As soon as the work cage 18 has turned a sufficient 90 distance so that the block 56 passes out of contact with the arm 55, the carrier plate swings upwardly, due to the tension of the spring 50, and moves the piece of work to one of the work receiving portions in the 95 work carrying cage. The carrier remains in the upper position until the next block 56 contacts with the projection 55. In the meantime the piece of work partially transferred to a work receiving portion of the cage is 100 rolled from the carrier 46 onto the incline 58 of the stationary member 17 and it gradually approaches the other member due to the shape of the lower annular grinding member.

To stop each work piece in the proper position on the carrier 46, I provide a stop member 60 which is clamped to the slide 35 by a cap screw 61. The member 60 is provided with an elongated slot 62 to permit adjustment to position the work pieces beneath the 110 openings in the cage.

The work carrying cage 18 may be suitably constructed to hold the work. As shown, it comprises a disk having a hub 64 mounted to rotate with the shaft 40 and it is provided 115 with a plurality of slots or openings 65 which are of the proper size to receive the objects 19 to be ground. The radial arms of the cage between the slots serve to locate the work pieces and to control their rotation. A ring 120 66 arranged around the periphery of the cage closes the ends of the slots and prevents escape of the work pieces as they revolve. In order to hold the work pieces properly for the grinding operation I provide contact 125 blades 67 suitably secured to the upper surface of the cage 18 adjacent the edge of each opening, as by means of screws. One edge of each block projects over the opening 65 and is provided with a beveled face 68 which acts to 130

receive the thrust of the upper rotating member and to maintain the work in contact with the lower member 17. This beveled face may be shaped to contact with the work above its center and near to the surface of the upper member so that its thrust is transmitted to hold the work firmly in contact with the lower member. In order to minimize the friction of the outer end of the work on the annular rim 66 of the cage, I prefer to employ an adjustable screw 69 (Fig. 7) which is arranged to engage the work piece and serve as a thrust bearing therefor.

In order that the work may be automatically discharged from the machine, after it has been reduced to size, I provide the stationary member with a downwardly sloping surface 70, located close to the work entrance so as to permit the pieces of work to roll into a receptacle or to a chute 71 which leads to the outside of the machine base. To prevent interference with the escaping work the arm of the lever 47 which is fastened to the spring 50 is offset, as shown in Fig. 10.

The surface of the stationary member 17 is so shaped that as the cage is revolved, the work is first swept off the carrier 46 up the inclined plane 58 and into contact with the rotatable member. The work is then given a combined rolling and sliding motion until it reaches the discharging slope 70, where it leaves the grinding zone. In the drawings, the rotatable member is shown out of contact with the work for clarity of illustration. The stationary member may be suitably shaped as desired or required for the particular work to be ground. The form illustrated diagrammatically in Figs. 6 and 8 has two active areas, the first part 75 having a gradual slope towards the rotatable member so as to reduce the work size and the second part 76 being substantially parallel with the surface of the rotatable member so as to permit that member to grind its way out and finish the surface of the work. By utilizing this construction for the stationary member the amount of lost motion in the grinding operation is reduced to a minimum.

The stationary element may be formed in any suitable manner, either as a rigid member or adjustable in shape. As shown in Fig. 9, the curvature may be changed at will by providing a flanged support 78, which may be mounted rigidly on the slide 35, and by forming the member of a flexible strip 79 which may be bent as desired by a series of push and pull screws 80 and 81. The screws 80 are threaded through the support 78 and push against the under surface of the strip 79. The screws 81 pass loosely through the support 78 and are threaded into the strip 79. This makes it possible to reduce or increase the amount of stock to be removed from the work and to vary the rate of grinding.

If it is desired to tilt the stationary ele-

ment laterally so that one may adjust it for wear as well as to make it feasible to grind either cylinders or tapered rolls, the construction shown in Figs. 11 and 12 may be used. The support 85, corresponding with the slide 35 of Fig. 1 has suitably fastened thereto the support 86 which in turn carries the annular member 87. In the form shown the member is made to provide two spaced surfaces 88 and 89 separated by a slot 90, so that the work may roll only on its ends and water and grit may fall into the slot and be carried therefrom through the openings 91.

Incidentally, it will be understood that suitable provisions may be made for the use of water during the grinding operation and for truing the grinding elements and otherwise carrying out the standard grinding practices which are applicable to a machine of this type.

The annular stationary element may be flexed and tilted by means of push and pull screws. The push screws 94 are threaded through the member 87 within the slot 90 and engage the top surface of a rib 95 on the support 86. The pull screws 96 likewise pass loosely through the arms 97 projecting laterally from the annular member 87 and are threaded into the ribs 98 projecting from the support 86. The long arms 97 make it possible to tilt the member laterally with a fine degree of precision.

It will be understood that the longitudinal flexing of the lower stationary element is ordinarily but a few thousandths of an inch, and that the surface of the lower element may be ground to form a portion thereof, as for example the plane portion 76 which is parallel with the upper annular face. It will be clear that the machine is applicable for grinding either cylindrical or tapered bodies, depending upon the shape of the stationary member and the openings in the cage will be formed accordingly. It will also be understood that the eccentricity of the cage and the rotatable element may be varied from zero to a desired extent. If the face of the rotatable element is wider than the work length, as shown in Fig. 4, the slide 35 may be adjusted so that the work just comes to both the inner and the outer peripheral edges of the abrasive annulus. Consequently, the face of the upper member will not be grooved but will remain substantially plane.

In the operation of my machine, assuming that the necessary adjustments have been made in the machine to handle the particular piece of work to be ground, the rough pieces of work are placed in a hopper feeding to the chute 45. As the cage 18 rotates, the blocks 56 successively contact with the projection 55 of the lever 47 and swing the lever periodically so that the carrier 46 moves downwardly into alignment with the lower surface of the hopper 45. The influence of

gravity on the work pieces in the hopper causes them to slide one at a time onto the carrier. The adjustable stop member 50 positions the work piece so that it is in alignment with an opening in the cage 18. When the block 56 passes over the top of the projection 55 the carrier 46 swings upwardly and moves the piece through an opening in the lower member and the side of a cage opening 10 engages the work and carries it from the carrier onto and up the sloping surface 58 of the work supporting member 17 until it comes into operative contact with the upper abrading element. The thrust of the upper rotating member holds the work against the beveled face 68 and the stationary member 17. The work is progressively fed upwardly toward the upper member because of the upward incline of the stationary member thereby causing a progressive grinding of each piece of work. When the work reaches the portion 76 of the stationary member which is parallel to the upper rotatable face, the upper member has an opportunity to finish the work surface. Thereafter, the work rolls down the curved surface 70 of the stationary member and out of engagement with the cage. As the grinding operation proceeds, the rotatable element may be fed downwardly by turning the hand wheel 30 as previously described to compensate for wear of the face of the upper element. The work cage serves to rotate the work during such times as it is out of contact with the upper element, and during the grinding operation it controls the work movement relative to both annular elements and about the cage center. The slope of the stationary member determines the amount of stock removed from the work during its single revolution.

By means of this apparatus, I am able to grind a large number of pieces of work to duplicate size each making but a single pass through the grinding zone. The length of the stationary member and the rate of rotation of the cage may be varied depending upon the type of work to be treated, and the parts may be variously arranged within the scope of my claims. The machine is fully automatic in its operation and requires the minimum of attention on the part of the operator.

Having thus described my invention, what I claim as new and desire to secure by Letters Patent is:

1. A grinding machine comprising a rotatable member having an annular abrading face, a work cage arranged to hold a plurality of pieces of work simultaneously in contact with said face, a member on the opposite side of the work cage and cooperating therewith to hold the work pieces in contact with said abrading member, means for rotating the cage eccentric to said abrading face so that the work will contact with the entire face, means to

rotate said abrading member and means for automatically loading pieces of work into said cage.

2. A grinding machine comprising two opposed members providing annular faces adapted to contact with and grind a plurality of pieces of work simultaneously, means to rotate one of said members, a rotatable work cage between said members arranged to maintain a plurality of work pieces in operative contact therewith, positively actuated means to move the cage during the grinding operation, and means for automatically loading pieces of work into the cage without removing it from the machine.

3. A grinding machine comprising two relatively rotatable members having opposed annular faces which cooperate to grind a plurality of work pieces, means to rotate one of said members, a cage rotatably mounted therebetween and arranged to hold a plurality of work pieces in operative contact with said faces, positively acting mechanism to rotate the work cage between said elements so as to revolve the work and cause a multiplicity of work pieces to be ground simultaneously, and mechanism which serves to feed work pieces to the cage during the grinding operation.

4. A grinding machine comprising two opposed members having annular faces which cooperate to grind a plurality of pieces of work simultaneously, means to rotate one of said members, a rotatable cage between said members arranged to maintain a plurality of work pieces in operative contact therewith, positively actuated mechanism to rotate the cage, a hopper to hold a plurality of unfinished work pieces, and automatically operating means cooperating with said cage to convey pieces of work successively from said hopper to the cage while the latter rotates.

5. A grinding machine comprising two opposed members providing annular faces adapted to contact with and grind a plurality of pieces of work simultaneously, a rotatable work cage between said members arranged to maintain a plurality of work pieces in operative contact therewith, positively actuated means for rotating the cage, and means for automatically discharging work pieces from the cage.

6. A grinding machine comprising two opposed members providing annular faces adapted to contact with and grind a plurality of pieces of work simultaneously, a rotatable work cage between said members and having provisions for maintaining a plurality of work pieces in operative contact with said members, means for rotating the cage, means for discharging work pieces from the cage after they have been finished, and means for loading the work cage with new pieces of work.

7. A grinding machine comprising two

- relatively rotatable members having opposed annular faces which cooperate to grind a plurality of pieces of work simultaneously, means for rotating one of the members, a 5 rotatable cage between the members arranged to hold a plurality of work pieces in operative contact therewith, positively actuated means to rotate the cage, and means to feed pieces of work successively to and discharge the 10 same from the cage.
8. A grinding machine comprising two elements having opposed annular faces which cooperate to grind a plurality of work pieces simultaneously, a work cage rotatably mounted therebetween and arranged to hold a plurality of similar work pieces in operative contact with said faces, positively actuated means to rotate the cage and cause the work pieces to revolve while remaining in a grinding relation to said elements, the face of one of said elements being so shaped that 75 the centers of the work pieces progressively approach the elements as they move through a single revolution about the cage center.
13. A grinding machine comprising two elements having opposed annular faces which 80 cooperate to grind a plurality of work pieces simultaneously, a work cage rotatably mounted therebetween and arranged to hold a plurality of similar work pieces in operative contact with said faces, means to rotate the cage and to cause the work pieces to revolve while remaining in a grinding relation to said elements, the face of one of said elements being so shaped that the centers of the work pieces progressively approach the elements as they move through a single revolution about the cage center, and 85 means to move one grinding element towards and from the other in order to accommodate different sizes of work.
9. A grinding machine comprising two relatively rotatable members having opposed annular faces which cooperate to grind a plurality of pieces of work simultaneously, 90 means for rotating one of the members, a rotatable cage between the members arranged to hold a plurality of work pieces in operative contact therewith, positively actuated means to rotate the cage, mechanism operating in timed relation to the cage rotation to feed pieces of work successively to the cage, and means permitting their discharge successively from the cage during the grinding operation.
10. A grinding machine comprising a rotatable grinding wheel having a plane annular face, an adjustable work support providing a substantially circular face opposed to the wheel face, means to maintain work pieces in operative engagement with and between said faces, and means for adjusting the shape of the work support to vary the distance of any part thereof from the grinding wheel.
11. A grinding machine comprising two opposed members providing annular faces adapted to contact with and grind a plurality of pieces of work simultaneously, a rotatable cage between said members adapted 115 to maintain a plurality of work pieces in operative contact therewith, means to rotate the cage, and means to rotate one of said members to grind the work, said opposed members being so shaped that the space therebetween progressively decreases from one point to another whereby 120 pieces of work introduced into the wider portion of said space will be progressively ground to a smaller size as they revolve between said members, and means for feeding work pieces successively into the wider portions of the space between said members.
12. A grinding machine comprising two opposed members having annular faces which cooperate to grind a plurality of pieces of work simultaneously, a rotatable cage be- 130

- tween said members adapted to maintain a plurality of work pieces in operative contact therewith, means to rotate the cage, one of said opposed members being so shaped that the space therebetween progressively decreases from one point to another whereby pieces of work introduced into the wider portion of said space will be progressively ground to a smaller size as they revolve between said members, means for feeding work pieces successively into the wider portions of the space between said members, and means permitting the work pieces to be successively discharged from the narrower portion of the space between said elements.
17. A grinding machine comprising a rotatable abrasive member having a plane annular abrading face, a work support presenting a track opposed to said wheel face, a rotatable cage eccentric with said member and arranged to maintain a plurality of work pieces simultaneously in contact with said abrading face and the track, means to rotate the abrasive member, means to move the cage eccentrically about the center of the abrasive member, and automatic means to convey work pieces successively to the cage and permit their discharge therefrom.
18. A grinding machine comprising a grinding wheel rotatable about a vertical axis which has a plane annular abrading face, a stationary work support beneath the wheel having a face which is eccentric with the wheel face, a cage rotatable about a vertical axis which is arranged to hold a large number of pieces of work simultaneously in grinding contact with said faces, said stationary support having an inclined portion which gradually approaches the grinding wheel face whereby work rolling along said inclined face will be reduced in diameter as it is ground, means for automatically introducing work to the lower portion of said inclined face and means for removing the work from the higher portion of the inclined face after it has made a single revolution around said stationary support.
19. A grinding machine comprising a grinding wheel rotatable about a vertical axis and having a plane face, a work support beneath the wheel having a circular member opposed to the wheel face, a rotary cage between said faces which is arranged to hold a plurality of work pieces simultaneously in grinding contact therewith, said cage and member being eccentric to the grinding wheel and the circular face having an inclined portion thereof which gradually approaches the wheel face so that work rolling along the inclined face will be reduced in diameter, means for adjusting the shape of the work support, means associated with said parts to feed pieces of work successively to the cage, and means for discharging the pieces one by one after they have traversed
- through substantially a complete revolution around the circular member.
20. A grinding machine comprising two opposed members providing annular faces adapted to contact with and grind a plurality of pieces of work simultaneously, a rotatable work cage between said members adapted to maintain a plurality of work pieces in contact therewith, a slide supporting said cage, and means to adjust said slide transversely.
21. A grinding machine comprising two opposed members having annular faces which cooperate to grind a plurality of pieces of work simultaneously, a rotatable work cage between said members arranged to maintain a plurality of work pieces in contact therewith, means to rotate one of said members and the cage relatively to grind the work, a slide supporting said cage, and means to adjust said slide transversely.
22. A grinding machine comprising a grinding wheel having a plane annular abrading face, a work support having a circular face opposed to said wheel face which progressively approaches it from one point to another in its circumference, a rotatable work cage between said wheel and support having a plurality of openings arranged to hold a number of pieces of work simultaneously in grinding contact with said faces, means to rotate the grinding wheel, means to rotate the cage, a slide mounted to support said work support and the cage, and means to move said slide to vary the eccentricity of the path of the work and the annular face of the grinding wheel.
23. A grinding machine comprising two opposed members providing annular faces adapted to contact with and grind a plurality of pieces of work simultaneously, means to maintain a plurality of work pieces in operative contact with both of said members during the grinding operation and means for adjusting the shape of one of said members to vary the distance of any part thereof from the other.
24. A grinding machine comprising a rotatable grinding wheel having a plane annular face, a flexible work supporting member opposed to the wheel face, a rotatable cage to maintain work pieces in operative engagement with the wheel and said member, and a support, and means cooperating with said support to adjust the shape of the flexible member.
25. A grinding machine comprising a rotatable grinding wheel, a lower work supporting element opposed thereto, means to maintain work pieces on the lower element in operative engagement with the wheel and means for tilting the work support laterally.
26. A grinding machine comprising a rotatable grinding wheel having a plane annular face, a flexible work supporting mem-

ber opposed to the wheel face, a rotatable cage to maintain work pieces in operative engagement with the wheel and said member, and a support, and means cooperating with said support to flex the flexible member both laterally and longitudinally and thereby to vary its shape and the distance of portions thereof from the face of the grinding wheel.

10 27. A grinding machine comprising two opposed elements having annular faces which cooperate to grind a piece of work, one of said elements having an opening therethrough which permits the feeding of work into the 15 grinding zone, a rotatable cage mounted between said elements and arranged to hold a plurality of work pieces simultaneously in contact therewith, and means for feeding work pieces successively through said opening into the cage.

28. A grinding machine comprising two opposed members having annular faces which cooperate to grind a plurality of pieces of work simultaneously, one of said elements 25 having an opening therethrough, a rotatable cage between said members adapted to maintain a plurality of work pieces in operative contact therewith, means to rotate the cage and revolve the work in operative relation 30 with said elements, means to rotate one of said members to grind the work, and means for feeding work pieces successively through said opening into the cage.

29. A grinding machine comprising two 35 opposed elements having annular faces which cooperate to grind a piece of work, one of which is inclined so that a piece of work revolving therebetween will gradually approach said elements, one of said elements 40 having an opening therethrough located in the widest space between said elements, a rotatable cage mounted therebetween and arranged to hold a plurality of work pieces simultaneously in grinding contact with said 45 elements, means to rotate the cage, and means cooperating therewith to feed pieces of work successively through said opening to said inclined surface and into operative engagement with the cage whereby the pieces of work 50 are moved up said incline into grinding contact with the elements.

30. A grinding machine comprising a rotatable element and a stationary element having annular faces which cooperate to grind a 55 piece of work, said stationary element having an opening therethrough, the face of said stationary element being inclined so that a piece of work moving from the opening will traverse into a narrower portion of the grinding zone, means to rotate said rotatable element, a rotatable cage between said elements arranged to hold a plurality of work pieces in grinding engagement with said elements, 60 means to rotate the cage, and means for loading pieces of work successively through said 65

opening into the cage and permitting the work pieces to be discharged therefrom.

31. A grinding machine comprising two opposed elements having annular faces which cooperate to grind a plurality of work pieces 70 simultaneously, one of said elements having an opening therethrough, a rotatable cage mounted between said elements and arranged to hold a plurality of work pieces simultaneously in contact therewith, means to rotate 75 the cage and revolve the work in operative relation with said elements, means for feeding work pieces successively through said opening into the cage, and a work carrying lever arranged to receive work pieces successively and present them through said opening into the cage.

32. A grinding machine comprising two opposed elements having annular faces which cooperate to grind a plurality of pieces of work simultaneously, one of said elements having an opening therethrough, a rotatable cage mounted between said elements and arranged to hold a plurality of work pieces simultaneously in contact therewith, means to rotate the cage and revolve the work in operative relation with said elements, means for feeding work pieces successively through said opening into the cage, a work carrying lever arranged to receive work pieces successively and present them through said opening into the cage, and associated means on said cage and said lever arranged to move the lever as the cage rotates to present work pieces 95 successively to the openings in the cage.

Signed at Worcester, Massachusetts, this 3rd day of June, 1927.

CHARLES H. NORTON.
